METHOD OF FINISHING METAL SHEETS

Alfred E. Hamilton, Pittsburgh, Pa.

Application November 22, 1939, Serial No. 305,639

2 Claims. (Cl. 29—18)

My invention relates to the finishing of metal sheets or strips, and more particularly to the treatment of sheets or strips of stainless steel, copper, brass, aluminum etc., to produce a mirror finish thereon.

One method heretofore employed in the finishing of strip steel comprises the steps of pickling the strip to cleanse it and remove scale therefrom; cold rolling the strip, and then passing it between rolls having very hard surfaces of mirror-like smoothness. However, the strips thus treated frequently do not have the desired high degree of brightness or polished appearance, because the pickling operation produces a greyish cast on the surface of the strip, which often is so pronounced as to resemble a stippled effect, and such appearance is not entirely eliminated by the cold-reducing rolls and the highly polished finishing rolls.

My invention has for its object the provision of a method of treating sheets whereby the said greyish cast or dull appearance is entirely eliminated, with the result that the sheets or strips are of more highly polished appearance than by the methods heretofore employed.

In the accompanying drawing the figure shows a schematic arrangement for practicing my invention.

It has been common practice to pass strips and sheets through pickling tanks and cold reducing rolls, in many instances the metal being also passed through scrubbing tanks after it leaves the pickling tanks. In the accompanying drawing, the metal strip to be treated is indicated by the numeral 1 and a pickling or scrubbing tank by the numeral 2. From the tank 2 the strip passes between a pair of cold reducing rolls 3, which may be driven in any suitable manner, and which serve to eliminate surface roughness on the strip. The strip passes between pairs of abrasive rolls 4 and 5. These rolls are driven in any convenient manner and may rotate in directions counter to the movement of the strip, or rotate in the same direction as the strip, but with a different rate of peripheral speed than the speed at which the strip moves.

More than two pairs of abrasive rolls 4 and 5 will usually be provided, in order to give sufficient abrasive capacity, and in order to avoid the necessity of frequent changes to provide fresh abrasive. The abrasive rolls which first engage the abrasive strip may carry abrasive of 240 grain size and the succeeding rolls carry 400 grain abrasive, though the final abrasive may be of the fineness of flour. The abrasive rolls may

suitably be in the form of pneumatic cylinders provided with abrasive sleeves, as shown for example in my Patent No. 2,113,836.

One advantage of using the pneumatic rolls referred to, is that by changing the air pressure within the rolls, a desired degree of abrading pressure on the strip can be had. Also, the abrading surfaces of the rolls will yield to follow uneven contours on the strip surfaces. It will also be understood that the strip can be passed directly from a pickling or scrubbing bath to the surfacing rolls 4 and 5.

The abrasive action of the rolls 4 and 5 is rather light as compared to heavy grinding operations. In many instances there will be only $\frac{1}{1000}$ of an inch removed from the strip, since the primary purpose of the abrasive action is to remove discoloration and any such slight roughness as remains after the strip passes through the reducing rolls 3.

From the rolls 5 the strip is carried through a tank 6 that contains water or other scrubbing liquid, wherein the sheet is scrubbed and washed by scrubbing rolls 7 to clear it of loose foreign matter. As the strip 1 passes out of the scrubbing tank, the major portion of the liquid is squeezed therefrom by the guide roller 15 which may suitably be of rubber and by a rubber squeegee bar 16, that extends crosswise of the strip and is so mounted as to exert substantial pressure thereon. The strip or sheet 1 then passes between hot air pipes 16 and 17 that are provided with orifices or nozzles through which warm air is projected to further dry the strip.

Thereupon the sheet passes between buffing rolls 8 that are covered with felt or built up of circular fibrous discs. A polishing compound will be employed with these rolls, numerous kinds of these compounds being well known on the market. Even though the strip which has a surface of matte appearance, as for example, unevenness such as is present on an orange skin, the low areas as well as the high areas will be highly polished.

A pair of rolls 9 covered with felt sleeves or brushes serve as wiping rolls to remove grit or particles of polishing compound from the strip.

The final finishing operation is performed on the strip by a pair of rolls 10 that have a mirror finish, to give the final desired high polish to the faces of the strip 1. The strip is wound upon a take-up reel or spool 11 that is driven with sufficient force, as through a friction drive, to coil the strip as it passes from the rolls 10. The advanc-

ing movement to the strip is imparted by the rolls 3 and 10.

A spool 12 carries a coil of paper 13, which is entered with the strip 1 upon the reel 11 and is drawn from the spool as the steel is wound upon the reel, so that it will prevent the turns of the steel 1 contacting and rubbing upon one another.

I claim as my invention:

1. The method of finishing cold-rolled sheets and the like, which comprises abrading and polishing the surfaces thereof to a depth not sub-

stantially in excess of that required for removing the roughness remaining after cold-rolling, buffing the sheets to a bright finish, and thereafter rolling them by mirror-finished rolls.

2. The method of finishing cold-rolled sheets and the like, which comprises abrading and polishing the surfaces thereof to a depth not substantially in excess of .002 inch, buffing the sheets to a bright finish, and thereafter rolling them by mirror-finished rolls.

ALFRED E. HAMILTON.
